INVENTOR.

UNITED STATES PATENT OFFICE.

FREDERICK SCHWINN, OF ATTLEBORO, MASSACHUSETTS.

DESIGN FOR A SPOON, FORK, OR SIMILAR ARTICLE.

48,916.

Specification for Design.

Patented Apr. 18, 1916.

Application filed January 27, 1916. Serial No. 74,708. Term of patent 7 years.

To all whom it may concern:

Be it known that I, FREDERICK SCHWINN, a citizen of the United States, residing at Attleboro, in the county of Bristol and State of Massachusetts, have invented a new, original, and ornamental Design for a Spoon, Fork, or Similar Article, of which the following is a specification, reference being had to the accompanying drawing, forming part thereof.

Figure 1 is a plan view of a spoon, fork

or similar article, showing my new design. Fig. 2 is a transverse sectional view taken on the line 2—2 in Fig. 1.

I claim:

The ornamental design for a spoon, fork or similar article as shown.

FREDERICK SCHWINN.
